[57] CLAIM

The ornamental design for a combined vent and baffle, substantially as shown and described.

DESCRIPTION

FIG. 1 is a top plan view of a first modification of a combined vent and baffle showing my new design;
 FIG. 2 is a side view of the left side of FIG. 1, the right side of FIG. 1 is a mirror image of FIG. 2;
 FIG. 3 is a bottom view of FIG. 1;
 FIG. 4 is an end view of the left end of FIG. 1;
 FIG. 5 is an end view of the right end of FIG. 1;
 FIG. 6 is a top plan view of a second modification of a combined vent and baffle of my new design;
 FIG. 7 is a side view of the left side of FIG. 6, the right side of FIG. 6 is a mirror image of FIG. 7;
 FIG. 8 is a bottom plan view of FIG. 6;
 FIG. 9 is an end view of the left end of FIG. 6;
 FIG. 10 is an end view of the right end of FIG. 6;
 FIG. 11 is a top plan view of a third modification of a combined vent and baffle of my new design;
 FIG. 12 is a side view of the left side of FIG. 11, the right side of FIG. 11 is a mirror image of FIG. 12;
 FIG. 13 is a bottom plan view of FIG. 11;
 FIG. 14 is an end view of the left end of FIG. 11; and
 FIG. 15 is an end view of the right end of FIG. 11.
